UNITED STATES PATENT OFFICE.

JOHN A. HUIZENGA, OF ROCK VALLEY, IOWA.

CHECK PROTECTOR.

Application filed July 19, 1920. Serial No. 397,367.

To all whom it may concern:

Be it known that I, JOHN A. HUIZENGA, a citizen of the United States, and a resident of Rock Valley, in the county of Sioux and

5 State of Iowa, have invented a certain new and useful Check Protector, of which the following is a specification.

The object of my invention is to provide a check protector of simple, durable and inexpensive construction.

10 More particularly it is my object to provide a device adapted to be used for protecting checks against alteration, the parts being so arranged that the numeral will be printed, together with the word representing that numeral. For example, if a check were to be written for \$5.12, the operator would move the device to 5, 1, and 2 and cause the printing operation to be had. The printing

20 upon the check would be such, that above the 5 would be the word "five," and above the 1 would be the word "one," and above the 2 would be the word "two."

Still a further object is to provide a series 25 of printing discs having levers fixed thereto, whereby each disc may be independently rotated, and a main operating lever for moving a printing platen towards the printing discs and causing a printing operation to be 30 performed.

Still another object is to provide in such a device an inking mechanism, which will operate just before the printing operation is performed and ink that portion of the printing discs that is about to print.

35 Still another object is to provide upon each printing disc a long bar, which will print on a check, printing directly behind the dollar sign that is originally on the check. 40 and touching the first figure or dollars portion of the check and also printing a bar between the dollars and cents portion of the check, and also printing through the name and through the date of the check, so as to 45 prevent any possible alteration of any nature whatsoever.

With these and other objects in view my invention consists in the construction, arrangement and combination of the various 50 parts of the device, whereby the objects contemplated are attained, as hereinafter more fully set forth, pointed out in my claims,

and illustrated in the accompanying drawings, in which:

Figure 1 shows a front elevation of my 55 check protector.

Figure 2 shows a central, sectional view taken on the line 2—2 of Figure 1, the position of the inking mechanism, being also shown in dotted lines.

Figure 3 shows a portion of a check printed thereon with my protector.

Figure 4 shows a central, vertical, sectional view taken on the line 4—4 of Figure 2.

Figure 5 shows a detail, side view of one 65 of the printing discs and the lever for controlling the same.

Figure 6 shows an end view of one of the printing discs; and

Figure 7 shows a detail, enlarged view of 70 the upper end of the disc operating lever.

In the accompanying drawings, I have used the reference numeral 10 to indicate an ordinary base, which is provided with a casing 11. The casing 11 is provided with end 75 walls 12 and 13 and with the rear or back wall 14. The forward or top wall of the casing 11 is curved at 15, as is shown in Figure 2 of the drawings.

Rotatably mounted within the end walls 80 12 and 13 is the shaft 16, which is provided with a crank handle 17 on one of its outer ends. The crank handle 17 serves as the main operating lever or handle, the operation of which will be more fully described.

85 Rotatably mounted on the shaft 16 is the sleeve 18. Mounted on the sleeve 18 are the printing discs 19, 20, 21, 22, 23, 24, 25, 26 and 27. Fixed to the printing discs just referred to are the handles or levers 28, 29, 30, 31, 32, 33, 34, 35 and 36 respectively.

90 Each of the handles or levers 28 to 36 inclusive extend through the slots 37 formed in the curved forward wall 15 of the casing 11. The levers at their outer upper ends are 95 bent a quarter turn, so as to form handle members. Each of the levers 28 to 36 are pivoted to their respective printing discs by means of the pivot 38.

100 Each of the discs are provided with flattened portions in their periphery on which is fixed the type 37 for printing. Each flattened portion is provided with a numeral and the word representing that numeral. For ex-

ample, the flattened portion having the number 4 thereon is also provided with the type for printing the word "four." Each of the discs is provided with an enlarged flattened portion 40, as illustrated in Figures 2 and 5 of the drawings, which have no type thereon, but cause a long bar to be printed across the check, when the disc is moved to the position where the flattened portion 40 will engage the platen.

10 The casing 11 adjacent to the slots 37 is provided with a series of notches 41, which are designed to receive and coact with the rib 42 formed on each of the handles or levers 27 to 36 inclusive.

15 On the casing 11 substantially adjacent to each of the notches 41 are the indicating characters 43. The levers 28 to 36 are adapted to move or slide within the slots 37 20 and are capable of being locked or yieldingly held in any position by the rib 42 being received within one of the notches 41.

25 It will be understood that the normal tendencies of the levers will be to rest within one of the notches 41, but when it is desired to move one of the levers, the operator grasps the lever at its upper end and moves it sidewise until it disengages the notch 41, and it is then free to slide within the slots 30 37. The locking of the levers within the notches 41 will keep the printing discs in proper position and prevent their accidental rotation.

35 When it is desired to move, say the disc 19, the lever 28 is engaged and moved forwardly within the slot 37. The moving of the lever in the direction indicated by the arrow 44 will cause the disc 19 to rotate upon the sleeve 18. In Figures 2 and 5 of 40 the drawings, it will be seen that the lever 28 is pivoted below the center of the disc and that the lever will rest against the sleeve 18. The forward movement of the lever 28 will cause the sleeve 18 to act as a 45 fulcrum for causing the disc 19 to rotate. After the disc rotates in the direction indicated by the arrow 44, the lever 28 will disengage the sleeve 18 as a fulcrum and would normally be moved outwardly out of 50 the casing 15. In order to take care of this lever movement, the forward wall 15 of the casing 11 is so formed that its lower end is a greater distance from the shaft upon which the discs rotate, than the upper edge 55 of the slots 37 are. This so provides that only a small portion of the levers will always extend out of the casing and through the slots 37 regardless of what position they are in.

60 Each of the indicating characters 43 are so placed on the casing, that when the lever, which is in the slot adjacent to it, is moved to position where it rests substantially adjacent to any of the indicating characters, 65 the corresponding figure and word on the

disc fixed to the lever will be moved to and remain in printing position. For example, if it was desired to print \$5.12, the lever 28 would be moved to 5, the lever 29 to 1, and the lever 30 to 2. This would cause the 70 discs 19, 20, and 21 to move to such position, that the numerals 5, 1, and 2 would be in printing positions, and also the words corresponding to those numbers.

75 On the lever 28 directly below the under surface of the casing 11, I have provided a stop 45, which will prevent the lever 28 from extending on through the casing 11. The remaining levers are provided with inclined portions 46, which prevent the possibility of the levers from extending on through the slots 37.

80 It will be understood that when the discs are rotated about half of their circumference, the pin or pivot 38 would be substantially above the shaft 16 or sleeve 18. If no stop were provided on the levers, they would merely extend on through or up through the slots 37. By providing the inclined portions 46 and the stop 45, this is 85 absolutely prevented, and in order to move or rotate the discs, it is necessary to draw the levers forwardly within the slots 37.

90 In order to ink the type desired to be printed, I have provided the following described mechanism:

95 Fixed on the shaft 16 is the pair of downwardly extending arms 47 and 48. Each of the arms 47 and 48 are provided with a pair of slots 49 and 50. Received within the 100 slot 50 is the shaft 51 and within the slot 49 is the shaft 52.

105 Fixed on the shafts 51 and 52 are the inking rollers 53 and 54. The roller 53 is of the type, which serves as a reservoir for 105 distributing or supplying ink to the roller 54, which is designed to come in contact with the type about to be printed from.

110 Each of the shafts 51 and 52 have fixed to their outer ends the bar 55. Springs 56 are provided, which have one of their ends 115 fixed to the bar 55 and the other ends fixed to the arms 47 and 48.

120 From the construction of the parts just described, it will be seen that the springs 115 56 will tend normally to draw the inking mechanism towards the upper edges of the slots 49 and 50.

125 Fixed on the base 10 are the guide devices 57, which are so formed that they engage the inking mechanism adjacent to each of the edges of the rollers 53 and 54. The guide devices 57 are bent upon themselves at their forward portion at 58, so as to form a downwardly extending curved portion 59.

130 Extending rearwardly from the curved portion 59 is the flat portion 60. The flat portion 60 is substantially in line with the printing position of the various discs. Near

the rear edge of the flattened portion 60 of the guide devices is the curved portion 61, having the downwardly extending portion

62. The curved portion 61 and the downwardly extending portion 62 of the guide devices 57 form a stop for the rearward movement of the inking device.

Fixed on the upper end of the arm 47 and substantially at right angles thereto is the arm 62^a. The arm 62^a sets adjacent to the end wall 12. Fixed on the shaft 16 by means of the set screw 63, adjacent to the wall 13 is the arm 64, which is substantially similar to the arm 62^a. The arms 62^a and 64 are each provided with the rollers 65 in their upper ends. Pivoted to the casing 11 are the bell crank levers 66, which are provided with the curved portion 67 at their upper ends. Pivoted to the forward ends 20 of the levers 66 is the platen 68 which is provided with the curved edges 69. The platen 68 is fixed or pivoted to the bell crank levers 66 by means of the pivot 70.

The upper ends of the levers 66 are in line with the arms 62^a and 64. The operation of the main crank handle 17 will cause the arms 62^a and 64 to move downwardly until their rollers 65 engage the curved portion 67 of the bell crank levers 66.

As soon as the arms 62^a and 64 engage the levers 66, they cause them to be moved to the position shown in dotted lines in Figure 2 of the drawings, thus causing the platen, which is pivoted to the forward end 35 of the bell crank levers to be raised forwardly until it strikes against the flat portions 60 of the guides 57.

In order to provide some means for returning or withdrawing the arms 62^a and 40 64 to their original position, I have provided the spring 71, which is fixed to the arm 64 and to the end wall 13. The spring will yieldingly tend to hold the arms 62^a and 64 in the position shown in solid lines 45 in Figure 2 of the drawings.

In order to cause the platen 68 to be moved downwardly or to inoperative position, I have provided the spring 72, which has one end fixed to the center of the platen 50 and its other end fixed to the base 10.

It will be seen that when the main handle 17 is operated or moved, which causes the arms 62^a and 64 to engage the bell crank levers 66, that it will also cause the arms 47 55 and 48, which support the inking mechanism to be moved to the position shown in dotted lines in Figure 2 of the drawings.

During the travel of the inking device, the rollers 53 and 54 will be drawn forwardly 60 and against the flat portions of the guide device 57, thereby causing the type which has been moved to position directly above the platen to become inked. The inking mechanism will be carried off of the flat portion 65 60 and out of the way before the roller 65

will engage the bell crank levers 66 and cause them to move the platen upwardly to printing position.

In order to form guides for holding the platen substantially horizontal in its upward movement, I have provided the curved guides 73, which are drawn upon a radius from the pivot of the bell crank levers 66. The platen 68 is provided with a pair of openings through which is extended the 75 guides 73. The guides 73 are formed substantially in the center of the machine, as is shown in Figure 4 of the drawings, and will not be in the road of any of the inking mechanism or the mechanism for causing the platen to rise and lower.

The platen 68 is provided with a stop 74, which limits the inward movement of the check. The end wall 12 is provided with a slot 75 through which is extended the check 85 or draft 76. The check or draft 76 is provided with the ordinary dollar sign 77.

In the practical operation of my device, the operator slides the end of the check having the dollar sign 77 thereon through 90 the opening 75 until it strikes the stop 74. It will be understood that the stop 74 may be made adjustable on the platen 68 in order to permit checks to be inserted further into the protector. When the check has reached 95 the stop 74, the operator then moves one of the levers, preferably the lever 28, until it rests against the indicating character bar. Then he moves the next lever, 29 for example, to 5, the lever 30 to the character bar, 100 the lever 31 to 1, and the lever 32 to 2. He then rotates the crank handle 17, which first inks the printing characters and causes the inking device to be held in the position shown in dotted lines in Figure 2 of the 105 drawings. Then the arms 62^a and 64 engage the levers 66, which causes the check and platen to be raised, until the check is in engagement with the inked characters on the discs. The springs 71 and 72 will tend to 110 cause the parts to be moved back to inoperative position. The check may then be withdrawn from the machine and will have printed upon it, the portions as shown in Figure 3 of the drawings, that is the bar, 115 then the 5 with the word "five" above it, then the bar, which indicates the cents lines, and the Figures 1 and 2 with the words "one" and "two" above them, which means that the check is for \$5.12.

By placing the bar directly in front of the first dollar figure and after the dollar sign 77, prevents anyone from inserting an extra numeral in order to raise or alter the check. The bar is comparatively long and extends 125 through the date as well as through the signature on the check, and thus prevents any alteration of that part of the check, as well as protecting the amount from being raised.

All of the levers which have been moved 130

to various positions are then moved to the extreme rear limit of their movement within the slots 37. When they are in this position, no printing characters will be in position to print.

5 The advantages of this device are that I am able to print the word and numeral together, so as to provide a double method of safety, and I use the bar between the dollars 10 and cents and before the first dollar figure and thus prevent any possible raising of the check. The fact that the bar extends through the date and the signature on the check also protects the check or draft against 15 any possible alteration.

Some changes may be made in the construction and arrangement of the parts of my improved check protector without departing from the essential features and purposes of my invention, and it is my intention to cover by my claims any modified forms of structure or use of mechanical equivalents, which may be reasonably included within their scope.

25 I claim as my invention:

1. In a check protector, the combination of a series of discs independently rotatable, means for operating them, each disc having upon a portion of its periphery a series of 30 flattened type surfaces, and each of said flattened type surfaces having thereon a numeral and a series of letters forming a word corresponding to the numeral, their printing surfaces being all on the same plane and 35 all of said characters being arranged to print one above the other in a single type

space, said discs being also each provided with an elongated line printing portion so arranged that when the line printing portion is placed in position for printing, between two of the printing discs having their type printing portions in printing position, an impression will be made of two numerals side by side with a type space between them and above each numeral a printed word corresponding to the numeral, and between the two numerals a printed line separating the numerals.

2. In a check protector, the combination of a series of discs independently rotatable, 40 means for rotating them, each disc having upon a portion of its periphery a series of flattened type surfaces, each being provided with type, said discs being also each provided with an elongated line printing portion 45 so arranged that when the line printing portion is placed in position for printing between two of the printing discs having their type printing portions in printing position, an impression will be made from the 50 two sets of type side by side and an elongated printing line between them, and whereby when the device is used for a check 55 protector and has type representing numerals, there may be printed directly in front of and close to the first dollar numeral an upright elongated line, and another immediately in the rear of the last dollar numeral, for the purposes stated.

Des Moines, Iowa, May 28, 1920.

JOHN A. HUIZENGA.
